(57) **CLAIM**

The ornamental design for a container cap, as shown and
described.

DESCRIPTION

FIG. 1 is a top plan view of a container cap, showing our
new design in a blank state, the bottom plan view being
identical; and,

FIG. 2 is a perspective view plan view of the container cap
of FIG. 1, showing our new design in place on a container.
The broken lines in the Figures are for illustrative purposes
only and form no part of the claimed design.
